United States Patent Office

Des. 196,653
Patented Oct. 22, 1963

196,653

TELEPHONE HANDSET

Charles F. Mattke, Fanwood, N.J., assignor to Bell Telephone Laboratories, Incorporated, New York, N.Y., a corporation of New York

Filed July 16, 1962, Ser. No. 70,932

Term of patent 14 years

(Cl. D26—14)

FIG. 1

FIG. 2

FIG. 3

FIG. 1 is a front elevational view of a telephone handset showing the new design;

FIG. 2 is an elevational view of the handset showing one side, the other side being essentially a mirror image of the side shown; and

FIG. 3 is a perspective view of the handset showing the bottom, one side and a portion of the front.

The characteristic features of the design are shown in full lines.

The shape of the outer periphery of the rear of the handset is identical to the front boundary as shown in FIG. 1.

The rear of the handset is a smooth unbroken curved surface, the over-all degree of curvature being shown in FIG. 2.

I claim:

The ornamental design for a telephone handset, as shown and described.
